UNITED STATES PATENT OFFICE.

JOHN A. SECOR, OF LAPORTE, INDIANA.

INTERNAL-COMBUSTION ENGINE.

1,269,007.

Specification of Letters Patent. Patented June 11, 1918.

Application filed April 16, 1915. Serial No. 21,875.

To all whom it may concern:

Be it known that I, JOHN A. SECOR, a citizen of the United States, residing at Laporte, in the county of Laporte and State 5 of Indiana, have invented a certain new and useful Improvement in Internal-Combustion Engines, of which the following is a specification.

My invention relates to improvements in 10 internal combustion engines, and has for its object to provide a new and improved form of combustion engine which will operate on low grade liquid fuels, and which will have those advantages heretofore confined to 15 "throttling" engines in which combustion occurs at constant volume with an increase of internal pressure. These advantages include moderate weight of power unit and cost of manufacture; high efficiency, both 20 mechanical and commercial; flexibility, including adaptability for high piston speeds and rotation rates. Added to these advantages, this engine will have the thermal efficiency of the high compression, constant 25 combustion pressure oil engine.

It is well known that, when a charge of air is drawn into the cylinder of a combustion engine, and is then compressed, the pressure may become so great that the heat 30 of compression will be sufficient without any other ignition means to ignite or fire the charge of fuel, and the so called Diesel motor is one of the best known motors operating under this principle. In such a motor, 35 special means are provided for injecting the fuel into the combustion chamber, because to prevent pre-ignition the fuel is not injected appreciably until the beginning of the power stroke. This necessitates means 40 for developing a pressure greater than the compression and combustion pressure of the engine for forcing the oil fuel in against that pressure. The oil fuel is fed into the cylinder at such a rate that the expansion 45 due to the heat of combustion keeps pace with the increase of volumetric capacity due to the movement of the piston, so that the pressure within the cylinder remains substantially unchanged until the fuel supply 50 is cut off by the governor, following which adiabatic expansion ensues and is accompanied by falling pressure to the completion of the working stroke in the usual manner.

In this arrangement, the fuel is injected 55 and burned gradually being mixed with the

air only as it burns, and the longer the burning continues the less freely does it take place owing to the natural decrease in the relative proportion of oxygen, that is to say, the oil or fuel which is injected into 60 the chamber burns slowly in the form of a continuous jet of flame because it is not intermingled with the air, as in the usual gas engine practice, and only that air which comes in actual contact with the oil fuel is 65 available for combustion. This results in slowing down the combustion and compelling the motor to operate at low speeds otherwise there is no time for combustion to take place or for the fuel to enter in. 70

The above must be contrasted with the ordinary combustion motor wherein the air and fuel are mixed and commingled before ignition so that each fuel particle is surrounded by its proper oxygen supply, thus permitting an almost instantaneous combustion of the charge extending throughout the entire combustion chamber, thus insuring the complete ignition under constant volume at the beginning of the stroke and allowing 80 expansion to do the work from then on. This of course permits higher speeds, and is one of the radical differences in performance between the high compression, slow burning constant pressure motor and the low compression constant volume explosion motor as now in use. In my arrangement I 85 propose to combine certain features of the low compression constant volume motor with the thermal advantages of constant 90 high compression at all loads and speeds.

My engine then is somewhat similar to the Diesel in that constant high compressions are used for a varying output of power, and that high temperatures are developed 95 in the combustion chamber by the compression employed. I propose to compel the air as it is inhaled uncontrolled and unthrottled during the suction stroke, to inhale with it the proper fuel supply, thus insuring a 100 mixing and commingling of the atomized fuel with the air, and rendering separate fuel injecting means, and fuel valves exposed to the heat and pressure of the compression and explosion pressures unnecessary. I propose, however, to add to the mixture a supply of water or other suitable 105 combustion retarding or cylinder cooling means such as will prevent self-ignition. At the appropriate time I will then fire the 110

charge with an electric spark in the usual manner.

The admixture of water with the fuel charge forms a fuel mixture of high specific heat, reducing the tendency to self-ignition at high loads and permitting higher compression, and if enough water is used the temperature may be held down to any desired point. The amount of water and 5 the amount of fuel may be varied. The quantity of air is always practically uniform, thus the volume of mixture entering is always the same, but it varies in richness, and the power output of the engine is 10 controlled by varying in thermal coordination the relative quantities of fuel and water. A full unthrottled air charge is thus inhaled at every charging stroke, as in Brayton or Diesel oil engines, or ordinary 15 20 "hit or miss" governed gas engines. It differs from the Diesel in that fuel and water are atomized by the entering air charge, being commingled therewith and inhaled as constituents of a homogeneous fuel charge, 25 thereby obviating the mechanical power loss involved by fuel injection under pressure in excess of the pressure of compression and combustion. It still further differs from the Siemens, Brayton and Diesel engines 30 in that combustion occurs at constant volume and not under constant pressure.

The supply of fuel and water is positively turned on and off in a pre-determined synchronous relation to the movement of the 35 engine intake valve, and is so timed that the fluid is turned off always except during that portion of the air intake stroke when the air velocity is at or near a maximum, thus all drooling and dripping and leaking 40 or seepage of the fuel and water from the supply nozzles at inopportune times is prevented, and only that amount of water or oil permitted to enter which is desired, and then only at the time when conditions are 45 such that a maximum atomizing effect is obtained. A governor is provided which varies the quantity of fuel fed by controlling the effective size of the liquid supply pipe to control the speed and power, and this 50 governor controls only the fuel and water, the air supply being always the same, the amount of air entering the cylinder for each stroke being the same, no matter what the speed or power.

55 My engine, therefore, takes in a constant volume of combustible mixture at each stroke. The mixture may be rich or it may be lean; it may have a maximum or it may have a minimum of fuel but it is constant in 60 volume. All the air passes through the Venturi tube and thus the problem of adjusting the relation between the engine and air and liquid is simple because there are no variable intakes, no throttle valves and no other 65 interfering elements to enter in and the air

velocity through the Venturi tube is in direct relation to the speed of the piston. I use a Venturi tube through which the air is drawn merely for the purpose of insuring maximum velocities of air and thus a maximum of atomization and mixing. Under some circumstances it might be desirable to dispense with the Venturi tube and use other arrangement of intakes. 70

My invention is illustrated more or less 75 diagrammatically in one form in the accompanying drawings, wherein—

Figure 1 is a detail elevation in part section,

Fig. 2 is a detail part section and part 80 elevation at right angles to Fig. 1.

Fig. 3 is a section along the line 3—3 of Fig. 2.

Like parts are indicated by the same letter in all the figures. 85

A is an internal combustion engine cylinder.

A¹ is a water jacket, A², the piston, A³, the intake, and A⁴, the exhaust valve. These two valves operate against the valve seats. A⁵, 90 are seated by springs A⁶, operated by levers A⁷. These levers are actuated by any suitable means not here shown.

B is an intake pipe discharging into the Venturi tube B¹ which in turn discharges 95 into the valve cage B² above the intake valve A³. B³ is an oil supply nozzle, and B⁴ a water supply nozzle, each discharging into the Venturi tube at the point of greatest contraction at right angles to the path 100 of air. B⁵ B⁶ are valve stems seated each upon one of the open nozzles B³ B⁴ by the springs B⁷. The washers B⁸ are adjustably mounted on the upper ends of the stems B⁵ 105 B⁶ in the path of one end of the rock lever B⁹. The rock lever B⁹ is pivoted on the bracket B¹⁰ and carries at its end the cross rod B¹¹. This cross rod extends at right angles to the rock arm, into the path of the washer B¹² on the upper end of the intake 110 valve stem, so that the downward movement of the intake valve will finally result in an upward movement of the water and oil valve stems.

C C¹ are oil and water reservoirs. They 115 communicate by means of passages C² C³ with the nozzles B³ B⁴. Each of these passages is controlled by a needle valve C⁴ operating against a seat C⁵ mounted on a screw-threaded valve stem C⁶. C⁷ C⁸ are oil and water valve levers. They are mounted on the stems C⁶, being angularly adjustable with respect thereto as indicated, and adapted to be locked in position with respect thereto by the screws C⁹, working in the 120 slots C¹⁰ in the short levers C¹¹, which levers are held against rotation on the stems C⁶ by the set screws C¹².

D is the governor rod. It may be actuated by a governor, a lever or any other 125 130

suitable member not shown here. It is pivoted on the lever C^2 and the pivot point may be adjusted therealong in the slot D^1 to change the throw of the lever in response to the movement of the rod, thus the fuel valve is positively connected to the governor rod. The water valve is connected to and controlled by the governor rod through the stub stem D^2 pivoted on the lever C^8 , the pivotal point being adjustable along the lever, the other end of the rod being provided with a collar D^3 free to slide along the governor rod and held against the collar D^4 by a spring D^5 , so that the governor rod 15 will be free to move forwardly to operate the fuel valve after the water valve has seated.

The use and operation of my invention are as follows:—

- 20 The piston in the drawings is shown at the beginning of the suction stroke. The intake valve is about to be opened. As it opens and as the piston descends a blast of air will be drawn in through the intake passage into the cylinder. The velocity of this air will increase rapidly from zero to a maximum and this maximum will prevail during what I prefer to call the mid stroke. As the intake valve stem descends the plate 25 carried near the top of upper end thereof will strike the rod mounted in the fuel control lever, will rock the lever and cause the lever to lift up on the fuel and water control valve stems. This will open the fuel and water nozzles and the fuel and water will be atomized by the rapid passage of the current of air across the edges of the nozzles and will be drawn as part of the charge into the cylinder. With the parts as shown the 30 intake valve opens partially before the movement of the fuel valve lever so that the liquid valves are neither of them open until the velocity of the air current is high, thus insuring complete atomization since no liquid is fed until the velocity of air is sufficient to insure satisfactory atomization. It 35 will be noted that the rocking lever strikes the washers held on the ends of the two liquid valve stems and since these washers may be adjusted in position the time when the valve stems themselves are moved may be controlled. As the piston approaches the lower end of this suction stroke the intake valve will commence to close in the usual 40 manner but before it seats and thus before the air current is shut off it will have risen sufficiently to permit the rock lever to move so that the springs on the upper ends of the lever valve stems will be able to insure seating of the liquid valves and thus a positive shut-off of the liquid supply before the end of the suction stroke and thus before the air velocity has fallen below the point at which satisfactory atomization takes place.
- 45 The oil and water is, of course, contained in reservoirs as shown and fed to the atomizing nozzles in the Venturi tube in the usual manner being controlled by the two needle valves. These needle valves are carried upon screw-threaded valve stems each stem 70 being controlled by a lever. These levers are adjustable in angular position with respect to the valve stems and are actuated or controlled by the governor rod as indicated. The governor rod is connected to the fuel 75 control lever and is connected by a sliding arm and spring to the water control lever so that the valves may be so adjusted that as the stem moves forward to close off the liquid it will first shut off the water completely and then subsequently shut off the fuel, the spring interposed between the governor stem and the water control lever being provided to permit movement of the governor rod and the fuel valve lever after the 80 seating of the water valve arrests the movement of the water valve lever. Of course, the governor rod might be actuated by any suitable means such as a governor in response to the load on the engine, a hand 85 lever or any other suitable mechanism.
- 90 The exhaust valve of the engine is operated in the usual manner by the valve lever which I have shown diagrammatically and it will be understood that the driving connection from the piston to the crank and shaft and the timing gears and the valve mechanism are all operated in the usual manner. The adjustment of the parts, is, of course, obvious. The two liquid valve levers 95 may be moved angularly with respect to the valves and the length of the lever arm may be varied to change the relative responses of the two valves with respect to the governor rod. The interval during which the supply of fuel and water is permitted I call the mid stroke and the cutting in and cutting out of these valves is effected near the ends of the stroke, but only during such mid stroke.
- 100 The result of so operating is, that there will be a very thorough and positive atomization and mixing of fuel and water with the air due to the high velocity and large volume of the air current flowing into the 105 cylinder. This thorough atomization of the fuel permits the use in the cylinder of high compression without self-ignition, so that the cylinder may, for example, in connection with the use of low grade liquid fuels, have 110 compression of say 100 pounds, although this figure is used merely for the matter of illustration. By in like manner thoroughly atomizing the water, which, by cooling the interior of the cylinder, has a retarding effect of ignition, it is possible to still further increase the compression in the cylinder to say, for example, 200 pounds without self-ignition. Of course, both of these results could be more or less secured by lead- 115
- 120
- 125
- 130

ing less than all of the air through the Venturi tube into which it goes, but this is obviously the preferred form of the structure. The compression in the cylinder can be increased in proportion to the thoroughness of the atomization of the liquid fuel, and again in proportion to the thoroughness of the atomization of the water, and by my arrangement the atomization of both can be carried to a point where the compression in the cylinder can be as high as is consistent with economic structure arrangements. Thus the preferred process involves the taking of the entire air supply through the passageway into which the fuel and water are discharged, and the discharge of fuel and water during only the mid-stroke.

The term "high compression" is, of course, relative, and moreover in designing an engine, many of the important features of my invention could be conserved without having a positively high compression. In such case, however, there would always be a constant compression pressure. If, therefore, in any given case, a designer wishes to use my invention, and dispense with the advantages incident to so-called high compression pressure, he may still secure the benefit of a constant compression pressure, because he will have a uniform and uncontrolled supply of air. By having this uncontrolled air supply and feeding the fuel or water, or both, in the manner proposed, he will get a constant compression pressure even at low pressures, and thus a high thermodynamic efficiency at low loads.

The arrangement can be such that either or both fuel and water can be thus introduced into a constant compression pressure cylinder when such pressure is either high or low, but preferably when it is high.

In order to make the foregoing description and the following claims clearly intelligible as to meaning and scope, it seemed best to explain the significance which I attach to certain words and expressions.

Where I have spoken of "constant compression", "constant volume", "constant quantity" and "uniform quantities" and the like, I mean, of course, to use these terms as if they were preceded by the word "approximately". When I speak of "uniform quantities" I mean to distinguish between the approximately uniform quantities as they are for example utilized in my invention where there is no throttling of the air, and the sharply varying successive quantities of air taken in to a cylinder where the operation involves the use of air throttling.

When I use the expression "constant compression", I mean thereby to indicate approximately a condition such as that which prevails in the Diesel engine.

By the use of the term "compression stroke", I mean the stroke of the piston dur-

ing which the charge is compressed in the cylinder.

By the expression "self ignition" I mean, of course, such ignition as takes place, for example, in the Diesel engine, or in any engine wherein ignition comes from the heat of compression.

By the term "ignition" not so modified or limited I mean, of course, ignition by separate means or means other than heat of compression.

By the expression "water" I, of course, mean water in any of its various forms.

By the expression "self ignition preventive" I mean any substance which applied or so mixed with the charge will tend to delay or prevent self-ignition.

I claim:

1. A combustion motor containing a cylinder, an air conduit with a Venturi tube portion to establish a high velocity air zone, engine controlled means for cutting the air current on and off, governor controlled means for delivering a varying supply of oil and water within such high velocity air zone and engine controlled means for cutting in the supply of oil and water after the air current has started and for cutting off the supply of oil and water before the air current has ceased.

2. A combustion motor containing a cylinder, an air conduit with means to establish a high velocity air zone, engine controlled means for cutting the air current on and off, governor controlled means for delivering a varying supply of oil and water within such high velocity air zone and engine controlled means for cutting in the supply of oil and water after the air current has started and for cutting off the supply of oil and water before the air current has ceased.

3. A combustion motor containing a cylinder, an air conduit, engine controlled means for cutting the air current on and off, governor controlled means for delivering a varying supply of oil and water to such air current and engine controlled means for cutting in the supply of oil and water after the air current has started and for cutting off the supply of oil and water before the air current has ceased.

4. A combustion motor containing a cylinder, an air conduit, engine controlled means for cutting the air current on and off, means for delivering a varying supply of oil and water to such air current and engine controlled means for cutting in the supply of oil and water after the air current has started and for cutting off the supply of oil and water before the air current has ceased.

5. A combustion motor containing a cylinder, an air conduit with a Venturi tube to establish a high velocity air zone, engine controlled means for cutting the air current

- on and off, governor controlled means for delivering a varying supply of fuel and a self-ignition preventive to the current and means for cutting in such supply after the air current has started and for cutting off the supply of fuel and self-ignition preventive before the air current has ceased. 6. A combustion motor containing a cylinder, an air conduit with a constriction to establish a high velocity air zone, engine controlled means for cutting the air current on and off, governor controlled means for delivering a varying supply of fuel and a self-ignition preventive to the current and means for cutting in such supply after the air current has started and for cutting off the supply of fuel and self-ignition preventive before the air current has ceased. 7. A combustion motor containing a cylinder, an air conduit with means to establish a high velocity air zone, engine controlled means for cutting the air current on and off, governor controlled means for delivering a varying supply of fuel and a self-ignition preventive to the current and means for cutting in such supply after the air current has started and for cutting off the supply of fuel and self-ignition preventive before the air current has ceased. 8. A combustion motor containing a cylinder, an air conduit, engine controlled means for cutting the air current on and off, governor controlled means for delivering a varying supply of fuel and a self-ignition preventive to such air current and engine controlled means for cutting in the supply of fuel and self-ignition preventive after the air current has started and for cutting off the supply of fuel and self-ignition preventive before the air current has ceased. 9. A combustion motor containing a cylinder, an air conduit, engine controlled means for cutting the air current on and off, means for delivering a varying supply of fuel and a self-ignition preventive to such air current and engine controlled means for cutting in the supply of fuel and self-ignition preventive after the air current has started and for cutting off the supply of fuel and self-ignition preventive before the air current has ceased. 10. A combustion motor containing a cylinder, an air conduit with a Venturi tube portion to establish a high velocity air zone, engine controlled means for cutting the air current on and off, governor controlled means for delivering a varying supply of fuel within such high velocity air zone and engine controlled means for cutting in the supply of fuel after the air current has started and for cutting off the supply of fuel before the air current has ceased. 11. A combustion motor containing a cylinder, an air conduit with means to establish a high velocity air zone, engine controlled means for cutting the air current on and off, governor controlled means for delivering a varying supply of fuel within such high velocity air zone and engine controlled means for cutting in the supply of fuel after the air current has started and for cutting off the supply of fuel before the air current has ceased. 12. A combustion motor containing a cylinder, an air conduit, engine controlled means for cutting the air current on and off, governor controlled means for delivering a varying supply of fuel to such air current and engine controlled means for cutting in the supply of fuel after the air current has started and for cutting off the supply of fuel before the air current has ceased. 13. A combustion motor containing a cylinder, an air conduit, engine controlled means for cutting the air current on and off, means for delivering a varying supply of fuel to such air current and engine controlled means for cutting in the supply of fuel after the air current has started and for cutting off the supply of fuel before the air current has ceased. 14. The combination with a constant compression combustion motor of means for supplying a combustible mixture of air, fuel and water thereto during the inhalation stroke and means for automatically varying the relative and total quantities of fuel and water responsive to variations in the load. 15. The combination with a constant compression combustion motor of means for supplying a combustible mixture of air, fuel and water thereto during the inhalation stroke, means for cutting off the fuel and water supply before the completion of the inhalation stroke and means for automatically varying the relative and total quantities of fuel and water responsive to variations in the load. 16. The combination with a constant compression combustion motor of means for supplying a combustible mixture of air, fuel and water thereto during the inhalation stroke, means for limiting the cyclic duration of the fuel and water admission period so as to synchronize approximately with period of high velocity of the inrushing air blast during the inhalation stroke, and means for regulating the engine speed by varying in due correlation the respective quantities of fuel and water contained in the fuel mixtures. 17. The combination with a constant compression combustion motor containing a cylinder, an air conduit with a Venturi tube portion to establish a high velocity air zone, of governor controlled means for delivering a varying supply of oil and water within such high velocity air zone during the inhalation stroke.

18. A constant compression combustion motor containing a cylinder, an air conduit with means to establish a high velocity air zone engine controlled means for cutting the air current on and off, governor controlled means for delivering a varying supply of liquid fuel and water within such high velocity air zone.

19. A combustion motor containing a cylinder, an air conduit, engine controlled means for cutting the air current on and off, governor controlled means for delivering a supply not varying of oil and water to such air current and engine controlled means for cutting in the supply of oil and water after the air current has started and for cutting off the supply of oil and water before the air current has ceased.

20. A combustion motor containing a cylinder, an air conduit with means to establish a high velocity air zone therein, engine controlled means for cutting the air current on and off, means for delivering a not varying supply of fuel within such high velocity air zone, and engine controlled means for cutting in the supply of fuel after the air current has started and for cutting

off the supply of fuel after the air current has ceased.

21. A constant compression combustion motor containing a cylinder, an air conduit with means to establish a high velocity air zone therein, a liquid fuel valve and a water valve each having outlet nozzles within the zone of maximum air velocity, engine controlled means for cutting a constant air supply on and off, engine controlled means for cutting in the supply of fuel and water after the air current has started and for cutting off the supply of fuel and water before the air current has ceased, with means for automatically varying the relative proportions of fuel and water in thermodynamic correlation with the power output and heat development so as to provide leaner fuel mixtures as the power demand decreases and richer mixtures as the power demand increases.

In testimony whereof, I affix my signature in the presence of two witnesses this 13th day of April, 1915.

JOHN A. SECOR.
